(57) **CLAIM**

The ornamental design for a jewelry item with charm, as shown and described.

DESCRIPTION

FIG. 1 is a front perspective view with chain of a jewelry item with charm;

FIG. 2 is a front perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is an exploded perspective view thereof;

FIG. 10 is a view showing infinite length thereof;

FIG. 11 is a front perspective view of a second embodiment thereof;

FIG. 12 is a front elevational view of a second embodiment thereof;

FIG. 13 is a rear elevational view of a second embodiment thereof;

FIG. 14 is a top plan view of a second embodiment thereof;

FIG. 15 is a bottom plan view of a second embodiment thereof;

FIG. 16 is a left side elevational view of a second embodiment thereof;

FIG. 17 is a right side elevational view of a second embodiment thereof;

FIG. 18 is a view showing infinite length of a second embodiment thereof;

FIG. 19 is a front perspective view of a third embodiment thereof;

FIG. 20 is a front elevational view of a third embodiment thereof;

FIG. 21 is a rear elevational view of a third embodiment thereof;

FIG. 22 is a top plan view of a third embodiment thereof;

FIG. 23 is a bottom plan view of a third embodiment thereof;

(Continued)

FIG. 24 is a left side elevational view of a third embodiment thereof;

FIG. 25 is a right side elevational view of a third embodiment thereof; and,

FIG. 26 is a view showing infinite length of a third embodiment thereof.

The broken lines shown in the drawing views are included for the purpose of showing environmental structure that forms no part of the claimed design.
